UNITED STATES PATENT OFFICE.

HENRY HEATON, OF CLEVELAND, OHIO.

FEED-WATER HEATER FOR LOCOMOTIVES.

SPECIFICATION forming part of Letters Patent No. 279,383, dated June 12, 1883.

Application filed February 13, 1883. (No model.)

To all whom it may concern:

Be it known that I, HENRY HEATON, of Cleveland, in the county of Cuyahoga and State of Ohio, have invented certain new and useful Improvements in Heating Feed-Water for Locomotives; and I do hereby declare the following to be a full, clear, and exact description of the invention, such as will enable others skilled in the art to which it pertains to make and use 5 to the same.

My invention relates to feed-water heaters, and more especially to heaters as applied to locomotive-engines; and it consists of certain features of construction and combinations of 15 parts, hereinafter described, and pointed out in the claims.

In the drawings, Figure 1 is a side elevation, and Fig. 2 a plan view, of a heater and so much of the locomotive-engine and its attachments as are needed to illustrate my invention. Fig. 3 is an end view of the cylinders and heater, and showing also the exhaust-pipes leading from the cylinders to the heater. Fig. 4 is a longitudinal section of the heater, and 25 Fig. 5 is a transverse section thereof.

A represents the boiler of a locomotive-engine; B B, the cylinders; C, the heater, and D the water-tank located in the tender.

The pipes b conduct the exhaust-steam from 30 the cylinders to the heater, and the pipe c conveys the remainder of the exhaust-steam that is not condensed in the heater to the tank D; and d represents a coil of pipe that is a continuation of the pipe c and immersed in the 35 water of the tank. These coils are to be of such condensing capacity as to condense all of the remaining exhaust-steam that comes from the heater. The feed-water is taken from the water-tank on the tender aforesaid through the 40 pipe F, and is forced by means of pumps, injectors, inspirators, or other devices through a pipe or pipes, C', within the heater, and thence into the boiler.

The pipe E, through which the water passes 45 from the heater to the boiler, is on the end of the heater that is nearest to the cylinders, and consequently at that end of the heater where the exhaust-steam is the hottest, while the pipe F, through which the water is forced from the

tank into the heater, enters the heater at the 50 end that is farthest from the cylinder—that is to say, the coolest end of the heater.

The operation of my device is as follows: The water when taken from the tank, if the engine has been running for a short time, is 55 already quite warm from two causes, first, from the heat from the coil d, wherein the condensation of the exhaust-steam is completed; and, second, the condensed water that is discharged from the heater and the said coil of 60 pipe d is at but little less than the boiling-point. This warm water then is forced through the heater, commencing at the end of the heater where the exhaust-steam is the coolest, and follows through the pipes C' in the heater 65 in the opposite direction from that in which the exhaust-steam that is surrounding the pipes is traveling. The result is that the feed-water rapidly increases in temperature as it passes along the heater, and till just as it is leaving the 70 heater to enter the boiler the pipes containing the said feed-water are exposed to the action of the hot steam direct from the cylinders striking against the said pipes, causing the feed-water to be raised to a very high temperature 75 as it goes to the boiler.

I do not limit myself to the construction herein described, or shown in the drawings, as a variety of ways might be employed for accomplishing the same object. 80

What I claim is—

1. The combination, with the cylinders B B, tank D, steam-pipe c, and water-supply pipes E F, of the heater C, provided with pipes C', and pipes b leading thereto, substantially as set 85 forth.

2. The combination, with the cylinders B B, tank D, coil d, steam-pipe c, and water-supply pipes E F, of the heater C, provided with pipes C', and pipes b b, substantially as set forth. 90

In testimony whereof I sign this specification, in the presence of two witnesses, this 23d day of January, 1883.

HENRY HEATON.

Witnesses:

C. H. DORER,
GEO. W. KING.
